UNITED STATES PATENT OFFICE.

JAMES B. HAMMOND, OF NEW YORK, N. Y.

TYPE-WRITING MACHINE.

SPECIFICATION forming part of Letters Patent No. 458,260, dated August 25, 1891.

Application filed April 21, 1890. Serial No. 348,828. (No model.)

To all whom it may concern:

Be it known that I, JAMES B. HAMMOND, of New York, in the county and State of New York, have invented a certain new and useful Improvement in Type-Writing Machines, 5 of which the following is a specification.

I will describe my improvement in connection with a type-writer of the kind which has heretofore been put upon the market as the 10 "Hammond" type-writer, and after doing so I will point out the novel features in claims.

In the accompanying drawings, Figure 1 is a horizontal section of a type-writer embodying my improvement. Fig. 2 is a sectional 15 top view of certain parts of the same which do not appear in Fig. 1. Fig. 3 is a side view of the principal parts of the type-writer. Fig. 4 is a vertical section of certain parts of the type-writer, taken parallel with the side of 20 the machine and made on a larger scale. Fig. 5 is a top view of a portion of a fulcrum-bar comprised in the machine, this view being made to the same scale as Fig. 4. Fig. 6 is a sectional elevation of one of a number of 25 fingers and an attached finger-piece. Fig. 7 is a top view of the finger shown in Fig. 6. Fig. 8 is a bottom view of the finger-piece shown in Fig. 6. Fig. 9 is a view similar to Fig. 6 of another of the finger-pieces. Fig. 10 30 is an enlarged elevation of certain parts.

Similar letters and figures of reference designate corresponding parts in all the figures.

A' A² designate two type-wheels or type-wheel segments arranged within a cylinder 35 B, having an opening, rearward of which are arranged an inking-ribbon R, a shield S for the ribbon, provided with a hole opposite the axis of the type-wheels or segments, and a holder for paper upon which writing is to be done. 40 Rearward of the hole in the ribbon-shield a hammer C is arranged. The type-wheels or segments are provided with different letters of the alphabet and other symbols which are to be printed. There are several rows of the 45 letters and symbols arranged one above another on the type-wheels or segments. Provision for a vertical movement of the type-wheels or segments is afforded to enable any row of letters or symbols to be presented in 50 a horizontal plane, which will enable them to be one at a time presented in a position opposite the hole in the ribbon-shield and the

hammer. The type-wheels or segments are adjustable rotarily to present the letter and symbols of any given row one at a time in a 55 position opposite the hammer. The hammer forces the paper upon which the writing is to be done against the inking-ribbon and the latter against a letter or symbol presented opposite the hole in the ribbon-shield. The paper is secured in a carriage W, which is moved in a direction parallel with the front of the machine and moved longitudinally by means of rollers, which are journaled in the carriage. The inking-ribbon R is made of more than 60 sufficient width to ink any letter or symbol upon either type-wheel or segment. It is supported by two spools R', upon which it is wound at the ends and upon either of which it is wound up to draw it along in order to 65 present fresh portions to the type-wheels or segments. The spools R' are arranged upon shafts R², which have a slow rotary motion during the operation of the machine. The spools rest upon collars r², which are affixed 70 to the shafts R². The spools may be clamped upon the shafts by expanding within them any suitable clamping devices attached to the shafts. There is nothing new at the present 75 time in the means for fastening the spools to their shafts or for driving these shafts. Hence I will not further explain the devices employed for these purposes. It will be seen that the spools have on one side bosses r of 80 very slight projection and at the other side bosses r' of considerably greater projection. This construction is important, because it enables the spools to be turned upside down to 85 present the ribbon in different planes to the type-wheels or segments, and thus offer fresh 90 surfaces for use.

D designates a number of key-levers or finger-keys. They are fulcrumed between their ends upon a bar d. At the rear ends they extend through slots in a bar d', and at the forward ends through slots in a bar d². The bars d' d² may be made integral with the base-frame F of the machine; but the bar d may be more advantageously made separate and secured thereto. A bar d¹⁰ extends across 95 the top of the bar d², thereby securing the key-levers in place. The front ends of the key-levers D extend to different points and are provided with upright fingers D', having 100

at their terminals finger-pieces D². The operator depresses the forward ends of these levers by manipulating the finger-pieces.

E designates levers, which are operated by 5 the key-levers D and serve to impart rotary motion to the type-wheels or segments. They consist, as here shown, of a rock-shaft e', arms e², extending forwardly therefrom, arms e³, extending horizontally toward each other obliquely across the rear end portions of the key-levers D and upright arms e⁴, which terminate at the upper extremities in fingers 1 that engage with pins 3 on the hubs of the type-wheels or segments to impart rotary motion to the latter. The arms e³ of each of the levers E extend over but one-half of the key-levers, and the upright arm e⁴ of each lever E operates solely upon one of the type-wheels or segments. The rock-shaft e', the arms e², 20 and the arms e⁴ of each lever E are shown as being made integral; but the arm e³ of each lever is detachably connected with the arm e² thereof. As here shown, each arm e³ is longitudinally slotted and is secured to the arm e² by means of a screw e⁵, whose body passes through the slot and engages with a hole in the arm e². By thus detachably connecting the arms e³ to the arms e² of the levers E provision is afforded for adjusting 25 the arms e³ into the best possible position to coact with the key-levers.

The key-levers not only serve to impart movement to the type-wheels, but also to operate devices whereby the positions in which 30 the type-wheels shall come to rest will be determined. For the latter purpose their rear end portions extend under a number of vertical stop-pins I so as to raise the latter when the forward extremities of said key-levers are depressed. These stop-pins are arranged 35 in an arc of a circle concentric with the axis of the type-wheels or segments, and they slide through two sector-shaped frames I' I², which are beneath a base-flange with which the cylinder B is provided. Between the frame I' 40 and collars or shoulders i, with which the stop-pins I are provided, springs i' are coiled around the stop-pins. These springs serve to depress the stop-pins, so that they will bear 45 upon the rear portions of the key-levers.

Whenever a key-lever is manipulated its rear end will not merely operate one of the levers E to impart rotary motion to the corresponding type-wheel or segment, but will also raise 50 one of the stop-pins I, so that it will project in the path of a stop-lever J. This stop-lever J is fulcrumed between its ends coincidently with the axis of the type-wheels or segments. Its forward arm projects over the frame I', so 55 that when moved it can be arrested by any one of the stop-pins I, which may be raised, and its rear end protrudes in the way of those ends of the type-wheels which are advanced to bring any letter or symbol arranged thereon 60 opposite to the hammer C. It will be evident 65 from this explanation that whenever the stop-lever is arrested by a stop-pin, the type-wheel

which shall up to that time have been moving will have its motion arrested.

It will be seen that the key-levers converge 70 rearwardly. This arrangement is due to the close proximity with which the stop-pins are located relatively to one another. They are not here shown as arranged to converge all to one point, but in two groups converging 75 toward two different points. By this arrangement of the key-levers they may be separated sufficiently well at the front ends and yet brought within a small compass at the rear ends. I have shown some of the levers bent 80 to one side at the forward ends for the purpose of securing the best possible arrangement between the three rows of finger-pieces.

It will be seen that because the front ends of the key-levers terminate in three rows 85 there is formed a key-board comprising three rows of finger-pieces. As the fingers D' supporting these three rows of finger-pieces are of different lengths, the three rows of finger-pieces are of different heights. The key-levers may be said to consist of three series 90 or sets. To equalize the leverage as far as practicable, the bar d has fulera in three different vertical planes. As here shown, the fulera are of inverted-V form and the key-levers are notched on the under side to fit upon such fulra. To avoid weakening the levers by the notches they may be bent or extended upwardly opposite the notches to conform in outline with the notched under 100 sides of the levers. The fulra or knife-edges, which are in three different planes, are marked d² d³ d⁴. It will be seen that the bar d is curved longitudinally and that the apices of the fulra d² are in one curved line or plane, 105 the apices of the fulra or knife-edges d³ are in another curved line or plane, and that the apices of the fulra or knife-edges d⁴ are in still another curved line or plane. The extension of the bar d and fulra d² d³ d⁴ in a 110 curve is advantageous owing to the convergence of the key-levers.

The carriage W is moved in the direction of its length by a spring in the usual manner. The means for controlling its movement are 115 so well known that I have not illustrated them in detail.

L designates a lever made in the form of a frame and fulcrumed at the rear end by pivots l. At the front of this frame-like lever there 120 is a cross-bar which extends above the rear portions of the key-levers D. Hence every time one of the key-levers is manipulated the lever L will be rocked upward. When so moved upward, the lever L effects the release 125 of the carriage and the carriage moves the distance required to properly present the paper to receive another letter or symbol. A lever D⁵, fulcrumed to one of the knife-edges d², extends rearwardly beneath the bar l' of 130 the lever L. This lever may be depressed at the forward end to effect the release of the carriage for spacing between words or sentences. Attached to the forward end of the

lever D⁵ is a bar d⁵, which extends parallel with the front of the front row of finger-pieces and for so long a distance as may be desired. The rear end of this lever D⁵ also extends under one arm of a lever M, which serves to prevent the hammer from operating at such times as the movement of the carriage is effected merely for spacing between words or sentences. This lever M is of ordinary construction. Hence I do not regard it as necessary to illustrate all the parts which coact therewith to preclude the operation of the hammer during movements of the carriage made for spacing between words and sentences. The bar d⁵ is supported not only by the lever D⁵, but also by two arms D⁶, which are pivoted by pins d⁶ to the base-frame F of the machine and are fastened by screws or otherwise to the under side of the said bar. Preferably the bar d⁵ will not be attached to the lever D⁵, but will rest upon it. A wire d⁷ may be fastened to the under side of the bar d⁵ to extend downward and laterally in the form of a hook beneath the forward extremity of the lever D⁵, so as to preserve the proper relations between the latter and said bar.

I will now explain the means whereby the type-wheels or segments may be elevated to present their different rows of letters and symbols into position for use. The hubs of the type-wheels or segments fit upon and are supported by an upright shaft Q. Under this extends a bent lever T, consisting of an arm t, extending widthwise of the machine and fulcrumed by a screw t' to an upward extension f' upon the base-frame of the machine. From the lever T an arm t³ extends rearwardly beneath the lower extremity of the shaft Q. To the arm t of the lever T an arm t⁴ is rigidly attached. This arm extends forwardly and has at its front extremity an upwardly-extending finger and a finger-piece attached thereto. The finger and finger-piece may be like the fingers and finger-pieces of the key-levers. On the finger-piece T² of the arm t⁴ I mark the letters "Fig." to indicate that by depressing this arm the type-wheels or segments will be elevated to a position which will bring the figure marked thereon in the same plane as the hammer C. A detent t⁵ is pivotally connected at its lower end by a screw t⁶ with the forward portion of the arm t⁴, and has near the upper end a hook, which may engage with a hole in the bar d¹⁰. It will be readily understood that the arm t⁴ may be depressed and retained in this depressed position to enable the figures on the type-wheels or segments to be used by merely swinging the detent t⁵ forward or lengthwise of the arm to engage with the bar d¹⁰ after the arm t⁴ shall have been properly depressed. A stop t⁷, consisting of a screw fitted in a tapped hole in a portion of the frame F and projecting upwardly under the arm t⁴, may limit the downward movement of the arm t⁴. Such stop may of course be adjusted as may

be desirable. The shaft Q is lowered by a spring in a well-known manner when released. The arm t, extending alongside of and normally on a level with the arm t⁴ and of the lever T, has also affixed to it an arm t⁸, which at the forward end is provided with a finger and finger-piece similar to the corresponding parts of the key-levers. This arm t⁸ is not, however, rigidly connected to the arm t of the lever T, but is pivotally connected thereto by the screw t', upon which the lever T is fulcrumed. This arm t⁸ is provided with a laterally-extending lug t⁹, which projects over the arm t⁴ of the lever T. Hence if the arm t⁸ be depressed it will effect the depression of the arm t⁴, and consequently cause an oscillation of the lever T and a raising of the type-wheels or segments. There is a stop t¹⁰ for limiting the depression of the arm t⁸ of the lever T, and this stop will preferably be made and fitted in place like the stop t⁷. The stops t⁷ t¹⁰ are so arranged that the arm t⁸ of the lever T cannot be depressed as far as the arm t⁴ of said lever. When the arm t⁸ is depressed, it will elevate the type-wheels or segments, so as to bring another row of letters or symbols opposite the hammer C. In the present instance it is intended that capital letters shall be brought into operation by the depression of the arm t⁸ on the lever T. Hence the finger-piece of this arm is marked with the letters "Cap." A detent t¹¹ is pivoted at the lower extremity to the arm t⁸ and provided near the upper end with a hook, which when said arm is depressed may be pushed lengthwise of the arm and engage with a hole in the bar d¹⁰, so as to hold the said arm depressed, and consequently maintain the type-wheels or segments in position for the continued use of capital letters.

In my type-writing machine the type-wheels or segments are removable from the shaft Q, whereby they are supported, and therefore others having different styles of letters may be substituted for them at will.

To provide for substituting different letters and symbols upon the key-levers D, so that the letters and symbols upon the key-levers may be made to correspond with those upon the type-wheels or segments, I preferably detachably connect the fingers D² with the key-levers. A convenient means of doing this consists in forming the fingers of pieces of sheet metal riveted or otherwise secured to the key-levers and extended upwardly to form pairs of resilient strips having the upper extremities turned laterally and provided with notches d¹³, and to form the fingers in the shape of buttons having pins d¹² extending from the under side and so disposed as to be able to engage with the notches in the laterally-turned extremities of the pairs of strips forming the fingers. Preferably the pins may be bent laterally to a slight extent, so as to be the more readily slipped into the notches.

What I claim as my invention, and desire to secure by Letters Patent, is—

1. In a type-writer, the combination of type-wheels or segments, a vertically-movable shaft upon which they are mounted, a lever for imparting vertical movement to said shaft, an arm secured to and extending forwardly from said lever, and another arm having a pivotal connection with the lever adjacent to the pivotal support of the lever and first-named arm, both of said arms extending forwardly side by side and normally on the same level, and the last-named arm having a projection extending over the first-named arm, substantially as specified. 5
2. In a type-writer, the combination of type-wheels or segments, a supporting-shaft therefor, a lever for imparting vertical movement to the supporting-shaft, arms extending forwardly from said lever, and a pivoted detent for each of said arms, the said detents having a movement lengthwise of the arms to engage with a portion of the machine-frame, substantially as specified. 15
3. In a type-writer, the combination, with the type-wheels or segments, the lever, and the arms extending forwardly therefrom, of detents pivoted to the arms and movable in the direction of the length of the arms to engage with a portion of the frame, substantially as specified. 25
4. In a type-writer, the combination of the type-wheels or segments, the single curved row of stop-pins therefor, the key-levers arranged in two groups and converging rearwardly and having their forward ends provided with finger-pieces arranged in straight parallel rows, levers intermediate of the type-wheels or segments, and key-levers and arms extending from the levers horizontally toward each other and obliquely across the rear end portions of the key-levers, substantially as specified. 35 40
5. In a type-writer, the combination, with type-bearers and an inking-ribbon, of spools for the ribbon mounted upon rotary shafts, the said spools having bosses on the opposite sides, the bosses on one side having a greater projection than the bosses on the other side, whereby when the spools are reversed a different plane of the ribbon will be presented to the type, substantially as specified. 45 50
6. In a type-writer, the combination of type-wheels or segments, key-levers, and levers E intermediate of the key-levers and type-wheels or segments and having arms e^3 , substantially as specified. 55
7. In a type-writer, the combination of type-wheels or segments, key-levers, and levers E intermediate of the key-levers and type-wheels or segments and having arms e^3 , provided with longitudinal slots and secured to the contiguous arms of said levers by means of screws passing through said slots, substantially as specified. 60
8. In a type-writer, the combination of a number of key-levers, pairs of resilient strips connected to the key-levers and terminating at their upper ends in laterally-extended flanges, and finger-pieces detachably connected with said flanges, substantially as specified. 65 70
9. In a type-writer, the combination of a number of key-levers, pairs of resilient strips connected to the key-levers and terminating at their upper ends in laterally-extended flanges, and finger-pieces having pins or wires engaging with notches in said flanges, substantially as specified. 75
